CLAIM

The ornamental design for a ruggedized remote control as shown and described herein.

DESCRIPTION

FIG. 1 illustrates a top perspective view of a ruggedized remote control.

FIG. 2 illustrates a bottom perspective view of the ruggedized remote control.

FIG. 3 illustrates a top plan view of the ruggedized remote control.

FIG. 4 illustrates a bottom-up view of the ruggedized remote control.

FIG. 5 illustrates a left-side view of the ruggedized remote control.

FIG. 6 illustrates a right-side view of the ruggedized remote control.

FIG. 7 illustrates a front view of the ruggedized remote control; and,

FIG. 8 illustrates a back view of the ruggedized remote control.

The broken lines in the drawings illustrate portions of the ruggedized remote control that form no part of the claimed design.
